Primary Examiner — Elizabeth A. Albert

(74) Attorney, Agent, or Firm — Patrick J. S. Inouye;
Krista A. Wittman(57) **CLAIM**

The ornamental design for a bottle opener, as substantially shown and described.

DESCRIPTION

FIG. 1 is a perspective view showing a bottle opener. FIG. 2 is a right elevational view of FIG. 1 thereof. FIG. 3 is a left elevational view of FIG. 1 thereof. FIG. 4 is a front plan view of FIG. 1 thereof. FIG. 5 is a back plan view of FIG. 1 thereof. FIG. 6 is a bottom elevational view of FIG. 1 thereof; and, FIG. 7 is a top elevational view of FIG. 1 thereof. The broken lines showing the corkscrew are included for the purpose of illustrating a feature that forms no part of the claimed design.
